The ornamental design for a gear lever, as shown and described.

DESCRIPTION

FIG. 1 is a front view of a gear lever of my present design; FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front, right perspective view thereof;

FIG. 8 is an enlarged detail view thereof, showing area 8 in FIG. 1; and,

FIG. 9 is an enlarged detail view thereof, showing area 9 in FIG. 4.

The dash-dash broken lines depict a boundary around de-emphasized elements, which illustrate portions of the gear lever which form no part of the claimed design.

The dot-dash broken lines represent the designation of the enlarged detail views and form no part of the claimed design.
